UNITED STATES PATENT OFFICE.

ARTHUR L. PICKERING, OF ANDERSON, INDIANA; FORREST M. PICKERING, ADMINISTRATOR OF SAID ARTHUR L. PICKERING, DECEASED, ASSIGNOR TO ECONOMY GOVERNOR COMPANY, OF ANDERSON, INDIANA, A CORPORATION OF INDIANA.

GAS REGULATOR.

Application filed May 2, 1924. Serial No. 710,684.

It is the object of my invention to provide a gas regulator in which the opportunities for leakage are reduced to a minimum both in respect to leakage from the gas main into the gas regulator when the valve is closed and in respect to leakage from the interior of the gas regulator to the outer air. A further object of my invention is to provide in such a gas regulator for the ready removal of the valve seat in order that it may be cleaned. A further object of my invention is to provide a means for supplying the valve leather of the regulator with oil or other liquid which will prevent its becoming dry and hard.

I accomplish the above objects by a novel method of pivotally mounting the lever which operatively connects the diaphragm of the gas regulator with the valve, by forming the valve seat in a plug or bushing which is screw threaded into the wall of the regulator and at its outer end is adapted to receive a pipe from the gas main, and I provide a supply of oil or other liquid which may be gradually fed to the valve leather in order to prevent its drying and becoming hard.

The accompanying drawing illustrates my invention: Fig. 1 is a plan view of an assembled gas regulator embodying my invention; Fig. 2 is a vertical section substantially on the line 2—2 of Fig. 1 showing the valve partially open; Fig. 3 is a fragmental section on an enlarged scale showing details of the valve and means for supplying the valve leather with oil; Fig. 4 is a perspective view of the valve with the valve leather and oil-feeding wicks in place; Fig. 5 is a perspective of the valve with the valve leather and wicks removed; and Fig. 6 is a view of the mold in which my gas regulator is cast showing the novel manner in which the lever is mounted.

My gas regulator comprises a casing 10, a cover 11 for such casing, a diaphragm 12 separating the casing from the cover, a valve 13, and a lever 14 by which movements of the diaphragm are transmitted to the valve so that when pressure in the casing 10 reaches or exceeds a predetermined value the valve 13 is closed. The diaphragm 12 is clamped between two disks of metal 15 and 16 by means of the screw 16'. To adjust the regulator to vary the pressure at which the valve 13 closes, I provide a screw 17, in a

boss 18 on the cover 11, and I interpose between the lower end of this screw and the diaphragm a coil spring 19. To prevent tampering with the adjusting screw 17, I prefer to provide a cap 20 which screws in place on the boss 18 and prevents ready access to the adjusting screw 17. The space within the cover 11 communicates with the atmosphere through a longitudinal hole in the screw 17 and a small hole in the cap 20.

At a point in the casing displaced from the center of the diaphragm 12, I mount a valve plug or bushing 25. At its outer end this bushing is provided with screw threads for the reception of the pipe 26 leading from the gas main. At its inner end, the valve plug 25 is formed with a central upstanding portion 27 which forms the valve seat, and surrounding this valve seat but spaced therefrom is a vertically extending annular flange 28.

The valve 13 is in the form of an inverted cup having a plurality of (preferably 3 or more) depending legs 29. In the bottom of the cup I cut one or more diametrically extending grooves 30 and at each end of each groove 30 I provide a slot 31 which extends from the bottom of the groove to the edge of the cup-flange. In each groove, I lay a piece of string 32, long enough to extend outwardly through the slots 31. The valve leather 33 fits tightly within the valve 13 and holds the strings 32 in position. When the valve 13 is in place on the valve seat 27, the ends of the strings 32 hang down into the annular space between the valve seat 27 and the flange 28. When this space is filled with oil, the string-ends serve as wicks which continually feed a small amount of oil to the valve leather 33, thus keeping such valve leather always soft and pliable.

The valve 13 is operatively connected to the diaphragm 12 by means of the pivoted lever 14. To this end, the disk 15 is provided with a downwardly extending ear 15' which, near its lower end, is provided with a hole for the reception of the end of the lever 14 which is preferably made cylindrical for this purpose. The cylindrical end of the lever 14 fits loosely in the hole through the ear 15'. The lever 14 is provided with two oppositely located, alined trunnions 14', each of which passes into a boss on the casing 10. To mount the lever 14 in this manner, it is supported in the mold in which the casing 10 is

cast in the manner shown in Fig. 6. The 5 trunnions 14' having been machined, the lever 14 is supported in the core 40 which is suitably recessed to receive the lever. Each 10 trunnion 14' projects outwardly from within the core into a depression 41 in the side walls of the core, and when the mold is poured the molten iron fills these depressions 41 to form the bosses in the casing 10. Before the mold 15 is poured, the trunnions 14' are coated with any suitable preparation which will prevent their adhering to the metal of the casing 10. I have found a suitable preparation for this purpose to be a mixture of graphite and core-wash. By this method of casting the casing 10 around the lever 14, the lever 14 is pivotally mounted without any necessity for holes through the casing which might prove 20 sources of gas-leakage.

20 My gas regulator operates in the same manner as similar gas regulators. The pressure in the main is communicated to the interior of the casing 10 and is normally insufficient to raise the diaphragm high enough 25 to close the valve 13. Under this condition, the gas flows regularly through the pipe 26 into the interior of the casing 10 and out through the outlet pipe 35. Should the pressure in the main increase, such increase is 30 communicated to the interior of the casing 10, the diaphragm is raised, and the valve 13 closed.

By making the valve seat 27 integral with the bushing 25, I eliminate the possibility of 35 leakage of high-pressure gas into the interior of the regulator when the valve is closed, while still permitting ready removal of the valve seat for the purpose of cleaning it. By the novel method of mounting 40 the lever 14, which requires no holes through the casing, I eliminate the possibility of leakage from the casing which would otherwise exist.

I claim as my invention:

45 1. A fluid pressure regulator, comprising a casing, a pressure responsive element, a bushing in the wall of said casing, said bushing having a valve seat at its inner end and being adapted at its outer end for connection to an inlet pipe, a valve co-operating with said valve seat, means supported independently of said bushing for operatively connecting said valve and said pressure responsive element, said bushing having a lubricant reservoir located below said valve seat, and said valve having one or more rigid legs which extend downward into said lubricant reservoir.

60 2. A fluid pressure regulator, comprising a casing, a pressure-responsive element, a valve seat, a valve co-operating with said valve seat, means for operatively connecting said valve and said pressure-responsive element, and a lubricant reservoir located below said valve seat, said valve being provided

ed with one or more rigid legs which extend downward into said lubricant reservoir.

3. In a fluid pressure regulator having a casing adapted to receive inlet and outlet pipes, a pressure responsive element, and a valve for said inlet pipe; a lever for operatively connecting said pressure responsive element and said valve, said lever having an integral laterally projecting trunnion which enters and is rotatably supported by a circular recess in said casing, such recess forming a bearing for said trunnion both above and below the trunnion axis, the outer end of such recess being closed by material integral with that of the casing, and the wall 80 of said casing opposite said recess being imperforate and formed entirely of material of which the remainder of the casing is formed.

4. In a fluid pressure regulator having a casing adapted to receive inlet and outlet pipes, a pressure responsive element, and a valve for said inlet pipe; a lever for operatively connecting said pressure responsive element and said valve, said lever having rigid with it two alined trunnions which enter and are rotatably supported by circular recesses in said casing, such recesses forming a bearing for said trunnions both above and below their common axis, the outer ends of both said recesses being closed by material integral with that of the casing.

5. In a fluid pressure regulator, a valve seat, a valve, said valve including a valve-leather which co-operates with said valve seat, a liquid reservoir, and one or more wicks in contact with said valve leather and extending into said liquid reservoir.

6. A fluid pressure regulator, comprising a casing, a pressure responsive element, a bushing in the wall of said casing, said bushing having a valve seat at its inner end and being adapted at its outer end for connection to an inlet pipe, a valve, said valve including a valve-leather which co-operates with said valve-seat, a liquid reservoir in said bushing, one or more wicks in contact with said valve leather and extending into said liquid reservoir, and means for operatively connecting said valve and said pressure responsive element.

7. In a gas regulator having a cast metal casing, a pressure-responsive element, a valve; a lever for operatively connecting said valve and said pressure-responsive element, said lever having a laterally projecting trunnion which is pivotally supported in said casing in a recess formed in said casing by said trunnion during the casting of said casing.

In witness whereof, I have hereunto set my hand at Indianapolis, Indiana, this 30th day of April, A. D., one thousand nine hundred and twenty four.

ARTHUR L. PICKERING.
